WINDING APPARATUS

Charles Robley Patterson, Albany, Calif., assignor
to Certain-Teed Products Corporation, New
York, N. Y., a corporation of Maryland

Application February 3, 1940, Serial No. 317,099

9 Claims. (Cl. 242—55)

This invention relates to machines for winding sheet material into rolls about a form and relates more particularly to mechanism for effecting removal of the roll from the form after being wound thereon.

The winding machines now commonly used are, in many cases, provided with a collapsible mandrel upon which the sheet material may be wound. It is usual to support the mandrel so that one end thereof is free of support. In order to expedite removal of a roll of sheet material from the mandrel, collapsing mechanism is provided which when operated acts to reduce the perimeter of the mandrel within the roll. The roll is then pulled manually off the collapsed mandrel over the free end thereof.

Although use of a collapsible mandrel is intended to facilitate removal, difficulties, nevertheless, may be experienced in removing a roll from this type of mandrel. These difficulties may be encountered because of variations in the conditions under which the winding operation is carried out. Variations in tension under which the sheet is wound or differences in the friction characteristics of the surface of the sheet in contact with the mandrel may occur. Particularly in the winding of heavy sheet materials, such as roll roofing or floor coverings, the weight of the rolls and the resultant relatively high friction between the mandrel surface and the inner periphery of the roll make it difficult for an operator to pull the roll endwise from the mandrel. Delays are thus caused which reduce output and increase the cost of the winding operation.

One of the objects of my invention is to provide mechanism which overcomes the above mentioned difficulties encountered in the removal of rolls of material from the mandrel of a winding machine.

A further object of my invention is to provide a mechanism for moving a roll along the mandrel toward the end thereof where it may be easily removed manually or handled by suitable transporting means.

Another object of my invention is to provide a roll moving mechanism for this purpose which may be easily installed on existing winding machines without interfering with the usual winding operation and the control thereof.

A still further object of my invention is to provide for actuation of the mechanism for removing the roll from the mandrel upon operation of the mandrel collapsing mechanism without additional effort on the part of the operator.

In its broader aspects my invention is con-

cerned with the provision of a device for engaging a roll wound on a mandrel which causes said roll to move along the axis of the mandrel. In the usual case where the mandrel is one which is supported so that an end thereof is free of support a device is arranged to effect said movement toward said free end so that the roll may be free of the mandrel at said end for further handling. In the preferred embodiment of my invention this roll-engaging device includes a member arranged to contact the end of the roll and to push it along the mandrel toward said free end thereof. Within the scope of the invention, however, other means and devices may be used to effect said axial movement of the roll, engagement of the roll being obtained by action of said roll engaging means on the roll at other portions thereof or on a carrier for the roll, if such is used.

20 The invention utilizes power actuated means which, within the scope of the invention, may be of different types and which may be so connected to the roll-moving mechanism as to effect the movement of the roll along the mandrel. To 25 accomplish control of the operation of the roll moving mechanism and of the power means which drives it, the invention provides devices which may be mechanical or electrical or combinations thereof which are so arranged in connection with the power means that control of the operation thereof is easily accomplished by the operator for the purpose of effecting removal of the roll from the mandrel and to permit restoration of the various mechanisms to the 30 condition where a new roll may be started.

To this end the control apparatus of the invention is so designed that the operation of the roll-moving mechanism is limited to the period or cycle which will include the movement of 35 the roll along the mandrel to its removed position and the return of the mechanism to its original position so that a new roll may be started. The power means and the mechanisms which connect it to the roll-engaging means, therefore, may be designed so that only a limited motion or period of operation thereof is brought about. The design of the controls also may be such that this limited motion or period of operation may be secured without regard to the failure or otherwise of the operator to effect release of the control from its operating position to which it has been moved at will by him for the purpose of effecting the removal of the roll.

A particular feature of the invention is that the devices for controlling the operation of the

power means and for effecting movement of the roll-engaging means to cause removal of the roll are so related to the mechanism for effecting collapse of the mandrel that when the operator operates the mechanism for collapsing the mandrel the power actuated means is brought into operation. Thereafter, in accordance with the invention, a limited period of such operation is secured by cut-off or releasing means designed to secure this limited operation. The cut-off or releasing means is so arranged that for a predetermined period of time or for a predetermined movement of the mechanism, such as the full movement forward and return of the roll-engaging device or for a predetermined part of said movement, the power is delivered to the roll-engaging device but thereafter is cut off.

The power source may be a rotating source such as an electric motor or it may take the form of a direct drive, either with or without intermediate mechanism, such as is provided by the fluid pressure cylinder having a piston connected to the roll-engaging means. Advantageously a rotating power source may be used which is connected to the roll-engaging and roll-moving mechanism through a clutch device of well-known type. This clutch device allows a predetermined rotational movement of the driven member thereof after the clutch has been engaged. Devices for effecting release and engagement of the clutch may be connected to the control members of the invention and particularly to the mechanism for collapsing the mandrel. The connection may be mechanical or preferably electrical and may be arranged to be actuated by the simple operation on the part of the operator of the mandrel collapsing mechanism. The device of the well-known type referred to may be designed to effect a single revolution of the driven member of the clutch and therefore lends itself to a simple connection to the roll-moving means so that a single revolution of the clutch effects a stroke forward and return of the roll-engaging member. Upon completion of this single revolution the device is stopped.

The invention, moreover, provides means designed to be self-limiting or for time or period limitation of its operation and arranged in connection with the power means of the type referred to to insure the predetermined movement thereof, such as a single revolution of the clutch or of the roll-moving mechanism itself. To accomplish this purpose the invention may utilize in certain embodiments electric control devices which are commercially available and which for the purposes of the invention have been arranged to cooperate with the control apparatus above referred to in order to insure the proper period of operation of the power means and the desired movement of the roll and of the roll-engaging means.

For a more complete explanation of my invention together with other objects and advantageous features and combinations of parts, reference may be had to the accompany drawings, in which

Fig. 1 is a side elevation of one form of push-off device of the invention.

Fig. 2 is an elevation of a modified form of the invention.

Fig. 3 is a section on line 3—3 of Fig. 2.

Fig. 4 is a cross-section of a collapsible mandrel taken on the line 4—4 of Fig. 2.

Fig. 5 is a schematic diagram of a preferred

electrical control system for the push-off device of the invention.

Fig. 6 is a clutch adapted to effect drive of the push-off device for a single cycle of forward and return movement.

In the embodiment of the invention illustrated in Fig. 1, a mandrel 1 of a conventional winding machine is shown with a roll 3 (in broken outline) wound thereon. The mandrel is supported at the left in the drawings by means not shown and has its end at the right free of support. A closed pressure cylinder 9 having a piston 11 slidably mounted therein is positioned with its axis parallel to the axis of the mandrel and offset therefrom. A rod 10 extending through stuffing box and guide 13 at one end of the cylinder 9, rigidly connects the piston 11 to pusher plate 5. A four way valve 21 is connected to direct the flow of a fluid under pressure, upon suitable operation, from a supply pipe 15 to a selected one of the delivery pipes 17 and 23 and thereby to the end of the cylinder to which the selected delivery pipe is connected. The valve 21 is so constructed that it connects the other end of the cylinder through the remaining delivery pipe to the discharge pipe 19. The supply pipe 15 may be connected to a fluid source such as steam, air, gas or liquid under a suitable pressure. Opposite ends of the cylinder 9 are connected by pipes 25 and 29 through an equalizing valve 27.

The operation of the device shown in Fig. 1 is as follows: Upon completion of the winding of a roll 3, the equalizing valve 27 is moved to prevent flow of fluid through pipes 25 and 29 between opposite ends of the cylinder 9. The four way valve 21 is moved to the position shown in full outline in Fig. 1 connecting the fluid supply pipe 15 with delivery pipe 17 and likewise connecting delivery pipe 23 to discharge pipe 19. The fluid pressure acting on the piston starts movement thereof toward the right in Fig. 1. Pusher plate 5, being rigidly connected to the piston 11 by rod 10, is moved into engagement with the end of roll 3 and pushes roll 3 along the mandrel 1 toward the free end thereof.

When the piston 11 approaches the end of its stroke, equalizing valve 27 is opened and allows free passage of the fluid through pipes 25 and 29 connecting opposite ends of cylinder 9. Thus a balance between pressures exerted on opposite sides of the piston may be effected which tends gently to stop movement of the piston. The length of stroke of the piston 11 and pusher plate 5 connected thereto is determined so that at its end position adjacent the free end of the mandrel the pusher plate 5 has effected movement of the roll 3 to a position for easy removal of the roll 3 from the mandrel 1.

The return stroke of the piston is effected by moving the four way valve 21 to the position shown in dotted outline in Fig. 1 and by again closing the equalizing valve 27. Fluid pressure is thereby applied through delivery pipe 23 to the right hand side of the piston 11 and the piston together with the rod 10 and the pusher plate 5 associated therewith is moved away from the free end of mandrel 1. When the piston approaches the end of the return stroke, the equalizing valve 27 may again be opened to cause the return movement of the piston to be gently arrested. Four way valve 21 may then be moved to a position which prevents flow of the fluid under pressure through the delivery pipe 23, and the winding machine is then ready to start winding another roll of material on mandrel 1.

While the valves 21 and 27 may be operated manually, I may interconnect the equalizing valve 27 with suitable valve gear of conventional type to the rod 10 so that the valve 21 may be operated by movement of the rod 10 without additional effort on the part of the operator. If in the device shown in Fig. 1, the mandrel 1 is of the collapsible type I may connect the valve 21 to the mandrel collapsing mechanism and effect flow through the valve 21 in accordance with operation of the mandrel collapsing mechanism, so that when the mandrel is maintained collapsed the valve 21 will be in the position shown in full outline in Fig. 1. When the collapsing mechanism is released the valve 21 will be moved to effect return of the piston to its original position.

In Figs. 2 and 3 I have shown an embodiment of my push-off device which utilizes a rotating source of power to drive the push-off mechanism. A similar arrangement may be used with direct acting power means, of the type disclosed in Fig. 1, which modification will be more fully described below.

The winding machine is provided with a collapsible mandrel which is driven from a rotating power source as by belt 73, running on pulley 71 keyed on a shaft extension of the mandrel 1 mounted to rotate on bearings 16 and 18 in base 74.

As can be seen by referring to Figs. 2 and 4, the mandrel 1 in the particular embodiment illustrated comprises a cylinder 2 having an opening 4 in the form of a slot extending from the free end of the mandrel for the full width of a sheet of material to be rolled thereon and used for insertion of the end of the sheet at the start of the winding operation. In suitable slots in the cylinder wall a plurality of roll supporting plates 6 are arranged to move radially outwardly from and inwardly toward the axis of the mandrel. The plates 6 are formed with cut-out portions 12 having the form of inclined planes. Conical wedges 7 are pinned to the mandrel collapsing rod 8 for movement therewith. The rod 8 extends through the support of the mandrel and end of rod 8 protrudes through the left of the support 14 where it may be contacted by the end 67 of the treadle lever system. A spring (not shown) tends to bias rod 8 toward the left side of Fig. 2 thus maintaining the mandrel 1 expanded by the action of the inclined surface of the wedges 7 on the inclined planes of cut-outs 12 of plates 6. When the rod 8 and wedges 7 are moved toward the right against the bias of the spring the plates 6 are free to move radially toward the axis of the mandrel 1 due to the sliding of the conical wedges 7 within the inclined plane portions 12 and thus the effective perimeter of the mandrel provided by the outer edge surfaces of the plates 6 may be reduced within a roll wound thereon.

A track 31 which may be of square cross-section is fastened to the base 74 and leg 80 of the winding machine by bolts or other suitable means to position said track with its length parallel to the axis of the mandrel 1, but offset from the axis of the mandrel 1 as may be seen by reference to Fig. 3. A carrier 33 provided with rollers 35 which contact and roll upon the track 31 is guided by the track to move therealong parallel to the axis of the mandrel. Pusher plate 5 is rigidly secured to one end of said carrier and is formed to contact a portion of the end surface of a roll 3 of material wound on the mandrel 1.

Connecting rod 37 loosely engages pin 38 which is fixed to the carrier 33. The other end of rod 37 is pivotally connected at 39 to one end of a lever 39 which is mounted at the other end thereof for angular movement about stud 41 as a fixed center. Intermediate the ends of lever 39 and pivotally connected thereto is a connecting rod 43. The other end of rod 43 is connected to a crank pin 40 on a crank disc 47 which is keyed to the driven shaft 48 of a clutch 49. The driving member of said clutch 49 may be keyed to a sprocket 96 driven by a chain 98 from a sprocket 104 on a power driven shaft 100. Also mounted on said power driven shaft 100 between bearings 106 and 108 held in supports 107 and 109 is a flywheel 102.

The clutch 49 may be of the type known as a single revolution clutch. The function of the single revolution clutch 49 is to transmit power between sprocket 96 which is to be run continuously and shaft 48 which is to be driven therefrom intermittently and which is to be stopped always in the same position.

The clutch 49 in the particular embodiment illustrated in Fig. 6 may comprise an outer race 200, an inner hub 201 having a plurality of flat surfaces 203 on the outer periphery thereof which extend parallel to the axis of the outer race and a cage 205 having rollers 207 mounted therein positioned between the outer periphery of the hub 201 and the inner periphery of the race. A cam 50 is fastened to the hub 201 to rotate therewith. A spring 202 may be provided normally so to position the cage 205 and hub 201 relative to each other as to cause the rollers 207 to become wedged in driving relation between the flat surfaces of the hub and the inner periphery of the driving race 200. When cam 50, however, is held against rotation the cage 205 and the hub 201 are so moved circumferentially relative to each other under the action of spring 202 that the rollers 207 are no longer wedged between the flat surfaces of the hub 201 and the race 200 and drive of the hub 201 and cam 50 through the clutch is stopped.

As shown in Fig. 2, trip 44 is mounted to rotate upon pin 51. This trip has an upwardly extending arm 45 and an arm 57 extending horizontally to the right in Fig. 2 as well as an arm 62 extending horizontally to the left. The pin 51 is carried in bracket 46 so located that the upper end of the upwardly extending arm 45 is adjacent the cam 50. This cam is provided with a step 52 which upon rotation of the cam contacts the end of the upwardly extending arm 45. Cam 50 is fastened to hub 201, Fig. 6. The hub 201 is keyed to shaft 48. Cam 50 and shaft 48, therefore, are rotated upon engagement of the clutch 49 of which the cam 50 is a part.

Link 42 connects at stud 53 from the outer end of the horizontally extending arm 57 of the trip 44 to the right hand end of portion 93 of lever 39 of the treadle mechanism. By a downward pull exerted on the stud 53 through the link 42 the upwardly extending arm 45 may be moved from under the step 52 of the cam 50. Under the action of the spring 202 the single revolution clutch 49 will be engaged and will cause the driven shaft 48 and the crank disc 47 carried thereby to rotate. Through the connecting rod 43 the push-off mechanism thereby is caused to operate.

To effect a single revolution of the driven shaft 48 the downward pull on the stud 53 may be removed before the revolution is completed. Tension spring 54 connected between stud 53 and

support 56, to which it is secured, exerts an upward force at the outer end of the horizontal arm 57 of the trip 44 and causes the upwardly extending arm 45 of the trip to follow the cam surface toward the center line of the shaft 48 until the trip arm 45 is again brought into contact with the step 52 of the cam 50. Thereupon the cam instantly actuates the mechanism of the clutch, as above described, to disengage the clutch and rotation of the parts connected to the driven member 69 of the clutch 48 ceases.

Unless prevented, considerable shock may be experienced when the trip arm 45 engages the step 52 formed on cam 50 and abruptly stops the driven mechanism at the end of the revolution of the shaft 48. To overcome this shock, I may provide a brake 58 having a drum 59 mounted on the driven shaft 48 of the clutch 48 to gradually slow down the driven shaft 48 as the end of the trip arm 45 approaches the step 52 of cam 50 near the end of a revolution. The brake 58 comprises a band 60 carried at one end by stud 12 mounted in support 56. The band 60 extends about the outer surface of the drum 59 and is adjustably connected by a threaded rod 66 at the other end thereof to portion 62 of trip 44. A light compression spring 55 is provided to determine the amount of braking effect exerted by the brake band 60 on the driven drum 59 and may be adjusted by means of nut 70. As can be seen from Fig. 3, rod 66 passes through an opening in portion 62 of trip 44 and is held from free movement therein by a stop nut 68, compression spring 55 and adjusting nut 70. The action of brake 58 may be increased by compressing the spring 55 on rod 66 between portion 62 of trip 44 and adjusting nut 70 by turning nut 70 clockwise. The braking force may be decreased by turning nut 70 counter-clockwise to reduce the compression of spring 55.

As stud 53 is pulled downwardly and trip arm 45 of trip 44 is moved out of engagement with the step 52 formed in cam 50, arm 62 of the trip 44 is caused to be moved upwardly against stop nut 68, thus removing the brake band 60 from frictional engagement with the brake drum 59 and allowing rotation of the driven member 69 and the push-off mechanism connected thereto. The invention provides means for removing the pull from stud 53 before the single revolution of the cam 50 is completed. The trip arm 45, following the cam surface, by action of tension spring 54 gradually tightens the brake band about the drum 59 due to the downward movement of arm 62 of the trip 44 acting through spring 55, rod 66 and nut 70.

The mandrel collapsing mechanism as shown in the particular embodiment illustrated in Figs. 2 and 3 comprises a treadle 61 rigidly connected to a lever 63 by a brace 64 and pivotally supported at 65 for movement in a vertical plane generally parallel with the axis of the mandrel 1. The upper portion 67 of the lever 63 is positioned to contact the end of the mandrel collapsing shaft 8. A lever 77 pivots on pin 78, held in support 81 intermediate the ends of said lever 77, and is positioned to move in a vertical plane transverse to the plane in which lever 63 and treadle 61 are free to move. The end 75 of lever 77 is arranged below the treadle 61 to be contacted thereby upon downward movement of said treadle. Portion 83 of the lever 77 is connected by a loosely fitting pin 85 to end 87 of lever 89. Lever 89 is pivotally mounted at 91 intermediate the ends thereof to move about pin

91 as center in a plane generally parallel with the plane of treadle movement. Portion 83 of lever 89 is loosely connected by pin 85 to link 42.

I may also substitute a ram or pressure cylinder of the type shown in Fig. 1 for the drive of the modification of the push-off device shown in Figs. 2 and 3. In this case, I may connect the piston rod 10 of the ram of Fig. 1 to the lever 89 by means of connecting rod 43. In this modification I may utilize a shorter stroke for the piston than that necessary for the mechanism of Fig. 1. In this manner the piston 11 and cylinder 8 may be positioned further from interference with the winding mechanism of the machine. The operation of the ram would follow the mode of operation described in connection with Fig. 1 above.

The operation of the machine shown in Figs. 2 and 3 is as follows:

The shaft 100, flywheel 102 and the connected members up to the driving member of clutch 49 are continuously driven from a power source not shown, when the machine is in operation.

The end of a sheet of the material to be wound into a roll is inserted into the slot 4 of the mandrel 1 (Fig. 4). Drive of mandrel 1 from pulley 71 is instituted by connecting belt 73 to a rotating power source. When the desired length of material has been wound on the mandrel 1, rotation thereof is stopped usually automatically by the control device of the winding machine. The mandrel collapsing treadle 61 then is depressed by the foot of the operator to allow the supporting plates 6 to be collapsed within the roll 3. As the treadle 61 travels downwardly it engages and moves end 75 of lever 77 in the same direction and causes lever 77 to rotate about pin 78 raising end 83 of lever 77. The end 87 of lever 89 will be moved upwardly in accordance with the upward movement of end 83 of lever 77. Lever 89 is thereby rotated about pin 91, lowering end 93 thereof and causing link 42 to move downwardly. As the link 42 moves downwardly it acts through pin 53 to cause trip arm 45 to move toward the right in Fig. 2 about pivot 51 away from the center of the driven shaft 48. The portion 62 of the trip 44 is correspondingly moved upwardly releasing the brake 58 and allowing the clutch mechanism to become engaged in driving relation to shaft 48 and crank disc 47 thereon.

The crank disc 47 starts to revolve in the direction indicated by the arrow and pivotal movement of the lever 89 is brought about through connecting rod 43. Connecting rod 37 between the end of lever 89 and the carrier 33 transmits the motion from the lever 89 to the carrier 33 and causes the carrier and the attached pusher plate 5 to be moved along track 31 toward the free end of the mandrel 1. The pusher plate 5 engages a portion of the end surface of a roll 3 wound on the mandrel and as the motion continues pushes the roll on the mandrel toward the free end thereof. When the push-off mechanism has reached the extreme position indicated in dotted outline in Fig. 2, the operator removes his foot from the mandrel collapsing treadle 61 and allows the spring (not shown) within the mandrel to raise treadle 61. The tension spring 54 then moves trip arm 45 into contact with the cam surface which is rotating. As the trip arm approaches the center of shaft 48 under the action of spring 54, gradually there is instituted action of brake 58 to slow down the movement of the driven members of the push-off device toward the initial position shown in full outline

in Fig. 2. When the carrier 33 and pusher plate 5 reach the position indicated in full outline in Fig. 2, the trip arm 45 contacts the step 52 formed on cam 50 immediately disengaging the drive through clutch 49 as explained above in connection with Fig. 6. Meanwhile, full braking action of brake 58 serves to stop motion of the driven portion of the push-off device simultaneously with the disengagement of the clutch.

For ease of operation and freedom from mechanical difficulties I prefer to utilize an electrical control system of the type shown in Fig. 5 to actuate the push-off device.

In schematic representation part of the mandrel collapsing mechanism is shown at 82 and comprises the mandrel collapsing treadle 61 and an arm 112 rigidly attached thereto for movement therewith.

Mounted on arm 112 is spring 114 specially formed of flat strip spring material and arranged to contact arm 116 of switch 115 to close the circuit through switch 115, momentarily, as the treadle is depressed. After the spring 114 passes beyond the arm 116 of switch 115, as shown in dotted line in Fig. 5, tension spring 118 returns the switch to open circuit position and maintains switch 115 in open circuit position away from contact point 117.

The armatures of solenoids 140 and 142 are mechanically connected respectively to the brake arm 160 and the trip arm 145 of the clutch 49. These solenoids 140 and 142 are electrically connected across an electric power line 148 through the respective contact points 134 and 136 of a two pole relay 130. The contact points 124 of a two pole relay 120 are electrically connected across the switch 115 and serve to maintain relay 120 energized from an alternating current line 128 after switch 115 has been actuated to allow flow of current therethrough momentarily.

At 110 is shown a vacuum tube time-delay relay of standard construction. The mechanism of the time delay device 110 may be of the type described in Patent No. 2,183,412 to Marvin B. Sledd, dated Dec. 12, 1939.

The operation of the time-delay device as embodied in the control of the invention is as follows:

The device is connected to an alternating current line 128 as shown. With the points 126 of the relay 120 open, the capacitor 152 tends to charge to the peak value of E which is adjusted by potentiometer 154. When a circuit is completed through the contact points 126 of the relay 120, the timing cycle is initiated. The voltage e applied to the grid 156 of the vacuum tube 158 is less than the voltage across the charged condenser 152, making the grid 156 negative with respect to the cathode 162 of the vacuum tube 158 and prevents flow of current through the tube. The condenser 152 slowly discharges through the resistor 164 until its voltage has dropped to a value less than e . This makes the grid positive and allows flow of current in the tube through the coil of relay 150. This current picks up the relay pole piece 151 and breaks the circuit through the switch points 166 of the relay 150, completing the time cycle. Adjustment of the potentiometer 154 determines the voltage charge of condenser 152 and hence the time period during which current may flow through the switch points 166 of relay 150. The timer is arranged to be reset when contact points 126 of the relay 120 are opened.

The operation of the push-off device using the

electrical control circuit of Fig. 5 is as follows:

The vacuum tube time-delay relay 110 is adjusted by means of potentiometer 154 to a time interval which is less than the period necessary for the push-off operation and return movement of the roll engaging means 5 to its initial position shown in full outline in Fig. 2.

Upon completion of the winding of a roll, the treadle 61 is depressed downwardly to collapse the mandrel 1 within the roll wound thereon. The spring 114 mounted on arm 112 of the treadle 61 is moved downwardly to momentarily close the electrical circuit through switch 115. After the spring 114 passes beyond the arm 116 of switch 115, as shown in dotted line in Fig. 5, spring 118 returns switch 115 to the open position. As the circuit through the contact points 166 of the time-delay relay 110 is normally closed the momentary closing of switch 115 causes current to flow from the alternating current line 128 to energize relays 120 and 130, closing the respective contact points 124, 126 and 134, 136 thereof. Contact points 124 serve to maintain relays 120 and 130 energized even though the operator may remove his foot from the treadle 61 after depressing it slightly without moving spring 114 down past the end of arm 116 as described. Closing of the circuit through contact points 126 which are electrically connected to the vacuum tube time-delay relay 110 initiates the time cycle.

When the relay 130 is energized contact points 134 and 136 serve electrically to connect solenoids 140 and 142 across power line 148 and the brake band 60 is moved out of contact with the driven drum 59 by the pull of solenoid 140 on the arm 160 the left hand end of which is moved into contact with nut 68. By the pull of solenoid 142 the clutch trip arm 145 is likewise removed from contact with the step 52 of cam 50 thereby causing the clutch 49 to start drive of the push-off mechanism as described above in connection with Figs. 2 and 6. The time delay relay 110 has been functioning in the meanwhile and upon elapse of the predetermined period of time, set by adjustment of potentiometer 154, which is less than that necessary for the push-off device to make one complete cycle, the relay 150 is raised to break the electrical circuit through its points 166. When the circuit through the contact points 166 of the relay 150 is broken, the relay 120 drops out and relay 130 immediately drops out as it is no longer energized. The solenoids 140 and 142 are electrically disconnected from line 148 by the breaking of the electrical circuit through contacts 134 and 136 of relay 130. Tension spring 146 then acts to cause trip arm 145 to follow the surface of cam 50 and tension spring 144 applies force on the brake arm 160 and thereby brings brake band 60 into frictional contact with the drum 59 on the driven shaft 48 and slows down the driven shaft 48. When the trip arm 145 again contacts the step 52 of cam 50 of the clutch 49, the clutch is caused to disengage and shaft 48 is held from movement upon the completion of the push-off operation.

I do not wish to limit my invention to the use of the exact form of time delay device shown at 110 as this type of relay is operable only from an alternating current source. I may substitute for said vacuum tube time delay relay any suitable electrical or mechanical device which will serve to open an electrical circuit after a predetermined rotation of the driven shaft 48 which is connected to roll-engaging means 5 of Figs. 2

and 3. Thermostatic or clockwork actuated switches may be substituted for relay 110 to make the device adaptable to any current.

In place of the double acting pressure cylinder shown and described in connection with Fig. 1 and referred to as a modification of Figs. 2 and 3, I may substitute a single acting power cylinder or other power source of the type which provides a forward power thrust stroke. When such a single acting power source is used I may utilize the power stroke to effect the movement of a roll along the mandrel and provide a spring or other bias means to effect the return stroke of the push-off device.

Having thus described my invention I now claim:

1. In a winding mechanism having a mandrel supported with one end thereof free of engagement with a support, a roll removing device comprising means operable at will for effecting actuation of said roll removing device, a track offset from said mandrel and like-extending with the axis of said mandrel, a carrier mounted on said track and constructed and arranged to move therealong, means carried by said carrier and constructed and arranged to engage a roll wound on said mandrel to move said roll axially toward the free end of the mandrel, a lever pivoted at one end and connected to said carrier at the other end thereof, a rotatable shaft, means connecting said shaft and said lever to effect pivotal movement of said lever upon rotation of said shaft, rotating power means for driving said shaft, a clutch connected between said power means and said shaft, means arranged to act on said clutch to effect engagement thereof for a predetermined rotational movement of said shaft, and means connected to said means operable at will and to said clutch engaging means to effect engagement of said clutch upon operation of said means operable at will.

2. A winding mechanism comprising a collapsible mandrel supported with one end thereof free of engagement with a support, means operable at will for effecting collapse of said mandrel, means constructed and arranged to engage a roll wound on said mandrel and mounted to move axially along said mandrel to effect movement of the roll toward the free end of the mandrel, a rotatable shaft, a crank on said shaft, a connecting rod connecting said crank to said roll engaging means to effect said movement thereof, rotating power means for driving said shaft, a clutch connected between said power means and said shaft, means arranged to act on said clutch to effect engagement thereof for a predetermined rotational movement of said shaft, and means connected to said means operable at will and to said clutch engaging means to effect engagement of said clutch upon operation of said means operable at will.

3. In a winding mechanism having a collapsible mandrel, a roll removing device comprising means for collapsing said mandrel, means constructed and arranged to engage a roll wound on said mandrel and mounted to move along the mandrel to effect movement of the roll axially on the mandrel, power operated means connected to said roll engaging means for effecting said movement of said roll engaging means upon actuation thereof, electrically actuated means connected to said power operated means and constructed to cause actuation of said power operated means upon energizing of said electrically actuated means, a switch arranged to close an

electrical circuit through said electrically actuated means, means operable at will for effecting actuation of said roll removing device, a connection to said means for collapsing said mandrel from said means operable at will to actuate the one upon operation of the other, and a separate connection to said switch from said means operable at will to close said switch upon operation of said means operable at will, said two connecting means being so constructed and arranged with respect to each other and to said means operable at will as to effect collapse of the mandrel concomitantly with the movement of the roll engaging means.

4. In a winding mechanism according to claim 3, means electrically connected in said circuit of said electrically actuated means to open said circuit after said roll engaging means has been moved a predetermined distance axially along the mandrel.

5. Winding means comprising a collapsible mandrel, means operable to effect collapse of said mandrel, means constructed and arranged to engage a roll wound on said mandrel and mounted to move along the mandrel to effect movement of the roll axially on the mandrel, a rotatable shaft, means connecting said shaft and said roll engaging means to effect said movement of said roll engaging means upon rotation of said shaft, rotating power means for driving said shaft, a clutch connected between said power means and said shaft and constructed to connect said power means in driving relation to said shaft for predetermined rotation thereof, electrically operated means constructed and arranged upon being energized to act on said clutch to cause engagement of said clutch, a switch arranged to close a circuit through said electrically operated clutch engaging means, said switch being connected to said means for effecting collapse of said mandrel and arranged to close said circuit upon operation of said means for effecting collapse of said mandrel.

6. In a winding mechanism according to claim 5, means electrically connected in said circuit of said electrically actuated clutch engaging means to open said circuit upon completion of a fraction of said predetermined rotation of said shaft.

7. In a winding mechanism having a collapsible mandrel a roll removing device comprising means to effect collapse of said mandrel, means constructed and arranged to engage a roll wound on said mandrel and mounted to move along the mandrel to effect movement of the roll axially on the mandrel, a rotatable shaft, means connecting said shaft and said roll engaging means to effect said movement of said roll engaging means upon rotation of said shaft, power means for driving said shaft, coupling means between said power means and said shaft constructed to effect connection and disconnection of said power means and said shaft, control means arranged to act on said coupling means to effect said driving connection therethrough for a predetermined rotation of said shaft, and means connected to said mandrel collapsing means and to said control means to actuate said control means to effect said driving connection through said coupling means upon operation of said means for effecting collapse of said mandrel.

8. In a winding mechanism having a collapsible mandrel a roll removing device comprising means to effect collapse of said mandrel, means constructed and arranged to engage a roll wound on said mandrel and mounted to move along the mandrel to effect movement of the roll axially

on the mandrel, power means to drive said roll engaging means to effect said movement thereof, coupling means between said power means and said roll engaging means constructed to effect connection and disconnection of said power means and said roll engaging means, control means arranged to act on said coupling means to effect said driving connection therethrough for a predetermined movement of said roll engaging means, and means connected to said mandrel collapsing means and to said control means to actuate said control means to effect said driving connection through said coupling means upon operation of said means for effecting collapse of said mandrel.

9. In a winding mechanism having a collapsible mandrel a roll removing device comprising means to effect collapse of the mandrel, means constructed and arranged to engage a roll wound on said mandrel and mounted to move along

the mandrel to effect movement of the roll axially on the mandrel, power means to drive said roll engaging means to effect said movement thereof, a clutch connected between said power means and said roll engaging means to effect connection and disconnection of said power means and said roll engaging means, means connected between said clutch and said mandrel collapsing means to cause said clutch to effect connection of said power means to drive said roll engaging means upon actuation of said mandrel collapsing means, said means connected between said clutch and said mandrel collapsing means including a device actuated upon driving operation of said power means and arranged to act upon said clutch to effect disconnection of said power means from said roll engaging means when said roll engaging means has completed one stroke toward the end of the mandrel and return.

CHARLES ROBLEY PATTERSON.
